UNITED STATES PATENT OFFICE.

MARK W. HOUSE, OF CLEVELAND, OHIO.

IMPROVEMENT IN ELECTRIC BATHS.

Specification forming part of Letters Patent No. 34,425, dated February 18, 1862.

To all whom it may concern:

Be it known that I, MARK W. HOUSE, of Cleveland, in the county of Cuyahoga and State of Ohio, have invented certain Improvements in the Apparatus through which to Apply Electricity in the Healing Art; and I do hereby declare the following to be a correct description of the same, reference being had to the accompanying drawings, in which—

Figure 1 is a longitudinal elevation of my improved bathing-tub. Fig. 2 is a transverse elevation. Fig. 3 is a view of the tub as seen from above.

The same parts are indicated by the same letters in all the figures.

The nature of my invention consists in the more perfect control of the electric current through the bath.

a in Figs. 1, 2, and 3 marks the tube, cylindrical in form, as shown at Fig. 2.

b shows a net-work non-conducting tray, in which the person rests while in the bath. This tray rests upon an insulated support, *J*, which runs the entire length of the base of the tray.

f are arms that are hinged at the center of each end of the tub, in such manner that either arm can be rotated freely about their center of motion without disturbing the other. It will be seen that these arms cannot make a complete rotary motion, in consequence of the interference of the support *J*. Upon these arms I place insulated metal conductors, shown at *c* in all the figures. These conductors or poles are charged with electricity through the connecting-wires *h h*. Attached to these poles *e* are sponges *d*, by means of a wire or flexible conductor, *h' h'*, shown in all the figures. These poles *e e* are so attached to the rotating arms *f f* that they can be freely traversed the entire length of them. By this simple arrangement of traversing and rotating the two poles of the current of electricity it can be controlled or caused to pass in any direction through the conducting medium. When either of the poles

e e are caused to rotate above the water-line, in case of a water-bath, the current will pass onto the sponge, which can be conducted to the proper place by the patient or the attendant.

The inclined end of the tray is designed for the head of the patient to rest upon. On the under side of this incline is hinged a good conducting metallic plate, in such a manner that it can be brought close in contact with the incline of the tray or be depressed at pleasure. By this arrangement the intensity of the current passing upon the head and neck can be regulated without changing the quantity. This metallic plate *c c*, as shown in Figs. 1 and 3, is supplied from the electric machine also by conducting-wires *h' h'*.

The manner of connecting the movable poles of the electric current with the electric machine in relation to the direction of the current or the positive and negative poles would depend entirely upon the object to be gained by the use of electricity.

I would further say that, in the construction of this bathing-apparatus, all materials used, except the electrodes, should be non-conducting, or made so by insulation, whether movable or stationary.

What I claim as my improvement, and desire to secure by Letters Patent, is—

1. The insulator *J*, for the support of the basket *b*, for the purpose described, in combination with the insulated rotating rods *f* and traversing-poles *e*, when arranged and operating as and for the purpose specified.

2. The head-plate *C*, when hinged to the insulator *J* in such a manner that the distance between the plate and head of the patient can be increased or diminished, for the purpose of concentrating or diffusing the electrical current through the part exposed to its action.

MARK W. HOUSE.
